(57) **CLAIM**

The ornamental design for a TV receiver, as shown and described.

DESCRIPTION

FIG. 1 is a front, right side, perspective view of a TV receiver showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, right side, perspective view thereof;

FIG. 9 is a front, right side, perspective view with its front display bending slightly, thereof;

FIG. 10 is a front view with its front display bending slightly thereof;

FIG. 11 is a rear view with its front display bending slightly thereof;

FIG. 12 is a left side view with its front display bending slightly thereof;

FIG. 13 is a right side view with its front display bending slightly thereof;

FIG. 14 is a top view with its front display bending slightly thereof;

FIG. 15 is a bottom view with its front display bending slightly thereof;

FIG. 16 is a front, right side, perspective view with its front display bending fully thereof;

FIG. 17 is a front view with its front display bending fully thereof;

FIG. 18 is a rear view with its front display bending fully thereof;

FIG. 19 is a left side view with its front display bending fully thereof;

FIG. 20 is a right side view with its front display bending fully thereof;

FIG. 21 is a top view with its front display bending fully thereof; and,

FIG. 22 is a bottom view with its front display bending fully thereof.

The broken lines indicate unclaimed portion of the article that form no part of the claimed design.

1 Claim, 17 Drawing Sheets
